(57) **CLAIM**

The ornamental design for a spring mount for a suspension, as shown and described.

DESCRIPTION

FIG. 1 is a perspective view showing the bottom, back, and left sides of a spring mount for a suspension having the inventive design;

FIG. 2 is a front elevational view of the spring mount for a suspension shown in FIG. 1, and the back elevational view is identical to the front elevational view of FIG. 2;

FIG. 3 is a right side elevational view of the spring mount for a suspension shown in FIG. 1, and the left side elevational view is identical to the right side elevational view of FIG. 3; FIG. 4 is a bottom view of the spring mount for a suspension shown in FIG. 1, and includes sectional lines 8—8 and 9—9; FIG. 5 is a top view of the spring mount for a suspension shown in FIG. 1;

FIG. 6 is a perspective view showing the top, front, and right sides of the spring mount for a suspension shown in FIG. 1; FIG. 7 is a perspective view showing the bottom, front, and right sides of the spring mount for a suspension shown in FIG. 1;

FIG. 8 is a sectional view of the spring mount for a suspension illustrated in FIG. 4, taken along sectional lines 8—8 thereof; and,

FIG. 9 is a sectional view of the spring mount for a suspension illustrated in FIG. 4, taken along sectional lines 9—9 thereof.

The sectional lines and sectional line reference numbers in FIG. 4 form no part of the claimed designs. The broken lines showing various holes in FIG. 1, FIG. 4, FIG. 5, FIG. 6, and FIG. 7 are for the purpose of illustrating an example of attachment holes of the spring mount and form no part of the claimed design.

1 Claim, 7 Drawing Sheets
